UNITED STATES PATENT OFFICE

2,592,651

STITCHLESS FLEXIBLE POCKET
RECEPACLEDouglas J. Broughton, Springfield, Mass., assignor
to Buxton, Incorporated, Springfield, Mass., a
corporation of Massachusetts

Application February 14, 1946, Serial No. 647,523

1 Claim. (Cl. 150—38)

1

This invention relates to an improvement in billfolds and more particularly to an end closure for the type of billfold having a transparent walled pocket for the display of an identification card, pass card or the like, and in which the billfold elements are held in place without the use of stitches.

The principal object of the invention is to provide an end closure construction by which improved flexibility is secured at the same time that the entire surface of the panels at the sides of the center fold line are made available for structural features such as a transparent window.

Other objects of the invention, and advantages, resulting from the details of the novel construction will be made apparent from the following specification and claim.

Fig. 1 is plan view of a blank from which a billfold embodying the invention may be folded up;

Fig. 2 is a plan view of the blank of Fig. 1 with the panel and certain of the flap members folded into place;

Fig. 3 is a view of the structure of Fig. 2 with the folding operations completed;

Fig. 4 is a sectional view substantially on line 4—4 of Fig. 3;

Fig. 5 is a view showing one end section of the billfold folded on the other; and

Fig. 6 is a view similar to Fig. 5 but showing a modified construction.

Referring to the drawings the blank is shown as comprising a rear wall member 1, end panel members 2 and 3 spaced from each other and each extending from the lower edge of the rear wall, and flap members 4 and 5 extending from the edges of panel members 2 and 3, respectively, opposite those edges of the latter which are attached to the rear wall. An end closing flap 6 extends from that end of the rear wall adjacent panel member 3.

Panel member 2 is provided with an end closure flap 7 extending from the outer end edge of the latter, the flap 7 terminating in a reduced tongue portion 8. Flap members 4 and 5 are provided at their outer end edges with tongues 9 and 10 respectively. As shown the upper edge of the rear wall member 1 and the portion of the lower edge of said member between the panel members are respectively provided with extending portions 11 and 12 which are folded over and cemented to the inner face of the rear wall in the usual manner to "finish" the exposed edge of the rear wall.

Panel member 2 is cut out as at 13 to provide

an open window frame. While the blank is in the form shown in Fig. 1 a piece of suitable transparent material 14 may be cemented or otherwise secured over the opening 13.

5 The positioning and application of the transparent member 14 is greatly facilitated since by the present construction it may be applied to the flat blank in advance of any folding operations which is not possible with present constructions

10 which avoid the use of stitching.

In folding up the billfold flap members 4 and 5 are respectively folded onto the adjacent panels 2 and 3 as shown in dotted lines in Fig. 1. The panels 2 and 3 are then folded onto the rear wall

15 1 as shown in Fig. 2 thus positioning the flap members 4 and 5 between the panel members and the rear wall. The end closure flap 7 and tongue are then folded rearwardly around the end of the billfold and onto the rear face of the rear wall 1, as shown in Figs. 3 and 5.

20 Preferably, as best shown in Fig. 1 the end of the rear wall adjacent flap 7 is cut away as indicated at 15 to a depth approximately equal to the thickness of the leather of flap 7. The center portion of the so cut away end of wall 1 is further recessed as at 16 to a depth substantially equal to the thickness of the leather of tongue 9. When the flap 7 and tongue 9 are folded around the end of wall 1 as above described they fit into the recesses 15 and 16 respectively providing a smooth edge at the end of the billfold. The tongue portion 8 of flap 7 is inserted in a slot 17 formed in the rear wall 1. The tongue 8 may be cemented to wall 1 inwardly of the slot 17 or interlocked in the slot in any usual manner.

25 Preferably the tongue portion 8 is additionally secured to the rear wall by a rivet 18 having a head in the form of an ornamental escutcheon plate 19 which may, if desired, be engraved with the initials of the owner or with any other marking.

30 At the other end of the billfold tongue 10 is folded over onto the outer face of panel 3, as shown in Fig. 2, and cemented thereto if desired.

35 Flap 6 is folded inwardly onto panel 3 as shown in Fig. 3, covering the inturned tongue 10.

30 The flap 6 may be interlocked to panel 3 in any suitable manner. As shown the free end of flap 6 is provided with a flexible plate 20 of thin plastic sheeting. Plate 20 is cemented or otherwise secured to an edge portion 21 of the flap 6. Plate 20 and the attached edge portion 21 are inserted through a slot 22, formed in panel 3, to extend toward the adjacent end of the billfold as shown in dotted line in Fig. 3.

At any suitable stage of the various folding operations above described an intermediate member 23 of conventional form and having projections 24 formed along its upper edge adjacent its ends, is inserted between the flaps 4 and 5 and their adjacent panel members, the projections 24 being inserted through slots 25 formed in flaps 4 and 5 in a known manner.

When as is frequently desired one end of the billfold is provided with a closure strap 26, Fig. 6, the escutcheon plate 19 may be replaced by a rivet in the form of one member 27 of a snap fastener, the other member 28 of the fastener being carried by the closure strap 26.

I claim:

In a billfold having a rear wall and a panel member extending from the lower edge of said rear wall and folded onto the inner face of the rear wall, an end closure flap extending from the end of said panel member which is adjacent the end of the billfold, a flap member extending from that edge of the panel member which is opposite the edge along which the panel member is attached to the rear wall, and being folded downwardly between the panel member and the rear wall, said flap member having a tongue extending from the end thereof which is adjacent the end of the billfold, said tongue being of less extent than said end closure flap, said last-named flap and said tongue being folded around the end of the billfold and onto the outer face of the rear wall, said tongue being positioned between

the end closure flap and the rear wall with its free end positioned short of the free end of the end closure flap and means securing that portion of the end closure flap lying beyond the free end of said tongue, to the rear wall of the billfold, said means comprising a narrow straight sided tongue extending from the free end of the closure flap and through a single slot formed in the rear wall and rivet means positioned beyond said slot and rigidly securing said straight sided tongue to the inner face of the rear wall.

DOUGLAS J. BROUGHTON.
